MANUFACTURE OF BRUSH EQUIPMENT

William F. Enchelmaier, Cedar Grove, N. J.

Application May 2, 1946, Serial No. 666,666

4 Claims. (Cl. 300—21)

1

This invention relates to the manufacture of brushing equipment. While it has particularly in view to improve and simplify the manufacture of rotary brushes and to produce an efficient and durable brush of the rotary type it is not to be understood that it is limited to such brushes in all respects.

In this art it is known to wrap a flexible strip in helical form, or it may be a number of flexible annular strips in side-by-side parallel disposition, around a cylindrical core and employ such strip or strips as an anchorage for tufts of bristles which are to project radially from the core, the anchoring being effected coincidentally with the wrapping. In order to form such tufts inherently as units to be employed in that procedure or my procedure hereinafter explained I propose as follows: A considerable number or cluster of bristles with their ends all in the same plane are to be gripped by a more or less narrow band in such manner that the latter projects beyond the said plane and thereby forms the resulting package with a well or sink. With this well facing upwardly, a layer, of suitable depth, of a suitable plastic (as rubber) in liquid state is to be deposited therein and then allowed to seep down between the bristles until their upper end portions become immersed individually therein for a suitable depth, as an eighth of an inch or more. The plastic is then to be set (as, in the case of rubber, by vulcanizing or curing) so that a unit is formed comprising the bristles and the plastic as a binding layer individually immuring their said end portions. Then in crossing equally spaced planes parallel with the bristles this unit is to be severed to produce a number of sub-units, or the required tufts, each comprising a group of bristles and a head which is a segment of the said binding layer.

The forming of a rotary brush in the manner above referred to is a slow and tedious operation, requiring considerable skill and care in its performance, i. e., because the anchoring of the tufts is effected coincidentally with the wrapping of the strip or strips around the core. According to this present invention the tufts, themselves produced generally in the manner above set forth, are made to form with a strip or other backing a unit; if such strip or other backing is flexible said unit may then be wound helically or otherwise around a suitable core in the forming of a rotary brush.

Such unit is formed, generally stated, as follows: Having the headed tufts, a settable plastic (as rubber) in suitably thick liquid state is de-

posited so as to form what I term an anchorage layer on a suitable backing and while this layer still remains in such liquid state the tuft heads are thrust into the layer, apparatus being present which at once supports the layer-coated backing and serves to guide the tufts. While the tuft heads remain thus in the anchorage layer the latter is made to set (as in the case of rubber, by curing or vulcanization). If, as in accordance with my specific purpose, the unit formed by the backing, anchorage layer and tufts when such layer has so set is to form a component of a rotary brush, i. e., to be wrapped around a suitable core, the setting referred to is developed only until the layer remains pliable. The backing in such case being of flexible material, as a suitable metal, said unit may then be flexed to the required form to fit the brush core and subjected to such treatment as will set the anchorage layer to the ultimate hard or approximately hard state required in the ultimate brush product.

It is of advantage to have each tuft headed, thus to exist as a unit. But there is this further important advantage: Without the heads and with the plastic that is to form the anchorage layer sufficiently free-flowing to impregnate the immersed bristles, by capillary attraction, the plastic would rise to leave the tuft rooted in a mound likely to encourage breaking off of the bristles when subjected to bending in the use of the finished brushing device. But with the heads present the liquid may be non-free-flowing wherefore on immersion of a headed tuft it cannot become rooted without depression of the layer at its surface and around the tuft, thus not to encourage breaking of the bristles. Preferably each tuft head is substantially quadrilateral in cross-section, with substantially the same number of bristles in all planes parallel with any of its sides (not true of the usual cross-sectionally circular tuft), giving it therefore increased sturdiness.

In the drawing:

Fig. 1 shows in side elevation, partly broken away, the mentioned package, with the plastic, which in liquid state was placed in its well or sink, having seeped down between the bristles and been made to set;

Fig. 2 is a top plan view thereof;

Fig. 3 shows one of the headed tufts developed from the package by severing;

Fig. 4 shows in side elevation, partly in section, the assembled apparatus, backing, anchorage layer thereon and tufts;

Fig. 5 is a fragmentary isometric view of the form of backing shown in Fig. 4;

Fig. 6 is a similar view of the assembled backing, anchorage layer and tufts; and

Fig. 7 is an end view of a cylindrical brush embodying an assembly of headed tufts and appearing partly in solid and partly in dotted outline.

In Fig. 1 a cluster of substantially equal-length bristles 1 is shown with the corresponding ends, as here the upper butt ends, of the bristles all in a common plane and the cluster tightly gripped by a band 2 whose upper margin extends above said plane and thereby forms with said ends of the bristles a sink or well 3; and into this well has been deposited a liquid plastic, as rubber, which has then seeped down between the bristles to the depth shown to form a binding layer 4 and thereupon has been set, as by curing, but (in this example) only to the state in which it is pliable. The resulting unit is then severed on the dotted crossing lines 5 of Fig. 2, producing the mentioned tufts *a*, headed at *a'*, such as is shown in Fig. 3.

At 6 is a suitable base having upstanding pegs or standards 6a which enter sockets 7 in a template 8, the template being thus removable. This template may have any form, as here elongated, and any required arrangement of holes 9, all here upright and parallel and penetrating it.

On the base is seated the backing 10, which for the purpose immediately in hand is of flexible material, as a metal. In this example the backing is a strip having its longitudinal margins upturned to form flanges 10a and to give the backing the form of a liquid-holder or sink; its resulting groove may have its otherwise open ends temporarily closed by some plastic masses, such as at 11.

With the backing seated on the base and the template in position, as shown, and with liquid plastic 12, as rubber, deposited on the backing, the tufts *a* are introduced, headed ends down, through the respective holes in the template and until their headed ends preferably rest on the backing and are thus immersed in the plastic layer 12 as shown in Fig. 4.

Thereupon, while the tufts are maintained in this state (as by preserving intact the assembly shown) the plastic 12 is made to set, as by vulcanizing, to form the anchorage layer but in the present example only to the state in which it is flexible. The plastic is of course of the class which, as rubber, in vulcanizing or curing will adhere to the backing.

The unit then formed by the backing, anchorage layer 12 and headed tufts is then removed from the apparatus comprising the base and template and subjected to such flexing as is required to adapt it to the particular curvature or other cross-sectional form of the core 13 of the ultimate brush to be produced, and when it has been flexed to such form it is subjected again to vulcanizing or equivalent setting step to convert the anchorage layer to the desired hard state. The material of the backing is preferably such that it retains substantially whatever state to which it is flexed.

As indicated, at the time of entering the tufts through the template their heads *a'* are still pliable so that, although they are polygonal and the (usually round) holes in the template so restricted in size as to grip firmly the tufts, such heads may by effort be forced through the holes.

In Fig. 7 a brushing device is shown in which whatever served (as the mentioned backing) to

support the anchorage layer at least until the headed tufts became anchored is omitted, having been removed.

When in the appended claims I use the term "headed tufts" I mean each of such headed tufts to include, with a tuft of bristles as that term is commonly used in this art, a plastic which exists impregnating a limited part of the length of such tuft at one end thereof and, by binding the bristles thereof together, forms with the tuft a unit.

In all aspects of my invention certain features hereinbefore referred to are not essential, for instance: That the binding medium *a'* for each headed tuft be set to some particular state (so as to be left pliable) when it is immersed in the anchorage layer; or that what I term the "body," as 12, in which the headed tufts become anchored be a layer in the sense that it has limited or moderate thickness; or that such body be in adhering relation to or otherwise associated with some form of backing in the brushing device that may be produced by resort to my method; or that, in the procedure by which bristles become rooted or anchored in a body which is initially a settable plastic in liquid state but ultimately is set to anchor the bristles, the latter necessarily are arranged in the form of tufts whether headed or not, or how the impregnating to form the binding layer 4 is effected.

Having thus fully described my invention what I claim is:

1. The method of forming a brushing device which consists in disposing a number of headed tufts in side by side relation and with their headed ends all directed toward and substantially coincident with a common plane, while maintaining the tufts thus related subjecting them, headed ends down, to immersion in, but so as to leave all the bristles thereof protruding from, a body of settable plastic in liquid state and, while the tufts are maintained so related and remain also immersed, setting said body to solid but only to flexible state, flexing the unit thus formed by the headed tufts and said body and, while said unit remains so flexed, setting said body to less flexible state.

2. The method of forming a brushing device which consists in disposing a number of headed tufts in side by side relation and with their headed ends all directed toward and substantially coincident with a common plane, while maintaining the tufts thus related subjecting them, headed ends down, to immersion in, but so as to leave all the bristles thereof protruding from, a body of settable plastic in liquid state and superimposed on a flexible backing to which said plastic will adhere and, while the tufts are maintained so related and remain also immersed, setting said body to solid but only flexible state, flexing the unit thus formed by the headed tufts, body and backing and, while said unit remains so flexed, setting said body to less flexible state.

3. The method of forming a brushing device which consists in supporting bristles in upright state and with their lower ends substantially coincident with a horizontal plane and immersed in a body of settable plastic in liquid state and, while said ends remain so supported and immersed, setting said body but only to flexible state, flexing the unit thus formed by the bristles and said body and, while said unit remains so flexed, setting said body to less flexible state.

4. The method of forming a rotary brushing device which comprises forming a body of settable

plastic in liquid state on one broad surface of an elongated flexible backing member to which said plastic will adhere, assembling a plurality of headed tufts of bristles in side-by-side relation and with their headed ends all directed toward and substantially coincident with a common plane, immersing the tufts maintained in such relationship with their headed ends down into the plastic on the flexible backing member, and while the tufts are maintained so related and their headed ends remain so immersed, setting said body of plastic to solid but only flexible state, bending the unit thus formed by the headed tufts, the plastic body, and the flexible backing member in a direction transverse to the longitudinal axis of the flexible backing member so as to form at least a substantial portion of an annulus, and while said unit remains so flexed

6
setting the plastic body to a substantially rigid state.
